UNITED STATES PATENT OFFICE.

WILHELM JASPER, OF NEW YORK, N. Y., ASSIGNOR OF ONE-HALF TO MAX MINDHEIM, OF SAME PLACE.

EXPANSIBLE PULLEY.

SPECIFICATION forming part of Letters Patent No. 593,895, dated November 16, 1897.

Application filed March 12, 1897. Serial No. 627,206. (No model.)

To all whom it may concern:

Be it known that I, WILHELM JASPER, a citizen of the United States, residing at New York, in the county and State of New York, have invented new and useful Improvements in Expansible Pulleys, of which the following is a specification.

The object of this invention is to obtain an expansion-pulley embodying certain novel features of construction, as set forth in the following specification and claims and illustrated in the annexed drawings, in which—

Figure 1 is a side elevation of alternating expansion-pulleys, one pulley being sectioned. Fig. 2 is a face view of a pulley of Fig. 1. Fig. 3 is a section along line *xx*, Fig. 1. Fig. 4 is a section along line *yy*, Fig. 1. Fig. 5 is a section along *zz*, Fig. 2. Fig. 6 is a detail view.

The disks 1 and 2 are shown with concentric axles 3 and 4. These axles or shafts are tubular, the axle 3 of disk 1 being inclosed in axle 4 of disk 2, so that each disk with its axle can be rotated relatively to the other disk and axle. The disk 1 is shown with rectilinear radiating slots 5 and adjusting-disk 2 with helical slots 6.

The belt-supporting lugs or bearing-pieces 7 are shown seated against a face of disk 1, with their stems 8 extended through slots 5 and 6. The stems 8 are suitably held in place, as by plates 9, secured by bolts or fastenings 10. The shaft 3 is shown with a rectilinear groove 11 and shaft 4 with helical groove 12. A roller-stud 13 engages said grooves 11 and 12. This stud 13 is carried by sleeve 14, engaged by fork 15 of a lever or shifter 16 and 17, fulcrumed at 18. When the sleeve 14 is shifted or slid along the shaft 4, the stud 13, engaging the grooves 11 and 12, will cause the shafts 3 and 4 with their disks 1 and 2 to rotate with respect to one another. The walls of helical slots 6 thus acting on stems 8 cause the latter, with bearing-pieces 7, to slide or be adjusted along the radial or guiding slots 5 toward or from the center of shafts 3 and 4. The radial rectilinear slots 5 guide the bearing-pieces directly to and from said center or shafts.

The handle or lever-arm 17 is shown with two alternating arms 16 and 16', so that while one pulley is expanded the other is contracted,

and vice versa. By spreading or concentrating the bearing-pieces 7, as stated, a belt supported on such pieces can be given a suitable tightening or bearing.

55

The walls of the guiding or rectilinear slots 5 are shown channeled, as at 19, Fig. 5, and the bearing-stems 8 have tongues 20 fitted or guided in said channels, so that the stems will suitably carry or hold the bearing-pieces 7 at 60 the face of guiding-disk 1. The shaft 3 is shown supported on stem 21, extending from support 22, which may also support fulcrum 18. When the tongues 20 engaging channels 19 are employed, the holding-plates 9, with 65 bolts 10, may be omitted, as the tongues 20 will prevent stems 8 from dropping or slipping out of place.

It is of course evident that the device may be modified, as the guide-slots 5 need not be 70 strictly rectilinear or might be placed at an angle to their position, as shown in Fig. 2, and still guide the bearing-pieces 7 from and toward the pulley center; also, in using two or more pulleys it is not necessary that the 75 helical or screw-thread slots or grooves 6 and 12 of the various pulleys should all correspond in pitch or size with one another. Such variations might be made and the relative rotation of disks 1 and 2 of a pulley would 80 still effect an adjustment of the bearing-pieces of such pulley.

The stud 13 is practically made four-sided or what may be called "lozenge-shaped," as seen in Fig. 6, where the stud 13 is shown 85 with four faces, two faces sitting against the edges of slot 11 and two faces sitting against the edges of slot 12.

What I claim as new, and desire to secure by Letters Patent, is—

90

1. A guiding-disk and an adjusting-disk, combined with concentric shafts for the disks, and bearing-pieces engaged by said disks, said shafts being respectively provided with helical and rectilinear grooves, and a sleeve 95 or shifter having a stud made to engage the grooves substantially as described.

2. A disk provided with rectilinear radial slots, combined with a disk provided with helical slots, bearing-pieces placed against one of 100 the disks and having stems extended through said slots, concentric shafts for the disks pro-

- vided respectively with rectilinear and helical grooves, and a sleeve or shifter having a stud made to engage said grooves substantially as described.
- 5 3. A guiding-disk provided with rectilinear radial slots, combined with an adjusting-disk provided with helical slots, bearing-pieces placed against one of the disks and having stems extended through said slots, concentric 10 shafts for the disks provided respectively with rectilinear and helical grooves, and a sleeve or shifter having a stud made to engage said grooves, said guiding-disk having its rectilinear slot walls channeled, and said 15 bearing-stems having tongues fitted into said channels substantially as described.
4. The combination with a guiding-disk

and an adjusting-disk provided, respectively, with rectilinear and helical slots, concentric shafts provided, respectively, with helical 20 and rectilinear grooves and connected with said disks, bearing-pieces engaged with the slots of the disks, and a shifter movable upon one of the shafts and having a stud engaging the rectilinear and helical grooves of said 25 shafts, substantially as described.

In testimony whereof I have hereunto set my hand in the presence of two subscribing witnesses:

WILHELM JASPER.
